(57) **CLAIM**

The ornamental design for a heat exchanger bag holder and bag, as shown and described.

DESCRIPTION

FIG. 1 is a front perspective view of the heat exchanger bag holder and bag, according to the present application;

FIG. 2 is a front view of FIG. 1;

FIG. 3 is a rear view of FIG. 1;

FIG. 4 is a bottom view of FIG. 1;

FIG. 5 is a top view of FIG. 1;

FIG. 6 is a side view of FIG. 1; and,

FIG. 7 is a side view of FIG. 1.

The shading is included to indicate contours and is not intended to indicate ornamentation.

The broken lines in the drawings depict portions of the heat exchanger bag holder and bag, and form no part of the claimed design.
